(57) **CLAIM**

The ornamental design for a scented urinal screen, as shown and described.

DESCRIPTION

FIG. 1 is a perspective view of the scented urinal screen, showing my design.

FIG. 2 is a front elevational view thereof;

FIG. 3 is a rear elevational view thereof;

FIG. 4 is a side elevational view when viewed from the right side;

FIG. 5 is a side elevational view when viewed from the left side;

FIG. 6 is a top plan view thereof;

FIG. 7 is a bottom plan view thereof;

FIG. 8 is a perspective view when the scented urinal screen is placed in the closed condition and acts as a funnel when placed in a urinal; and,

FIG. 9 is a perspective view of the scented urinal screen in the closed condition which has a cone shape when placed in a urinal.
